(57) **CLAIM**

The ornamental design for a pool table leg, as shown and described.

DESCRIPTION

FIG. 1 is a side elevational view of a pool table leg of my new design.

FIG. 2 is a front elevational view of a pool table leg of my new design.

FIG. 3 is an enlarged front view of the pool table leg.

FIG. 4 is an enlarged side view of the pool table leg.

FIG. 5 is an enlarged top view of the pool table leg; and,

FIG. 6 is an enlarged bottom view of the pool table leg. The broken line showing of a pool table is for illustrative purposes only and forms no part of the claimed design.
